ROOFING STRIP

William B. Robinson, Sayville, N. Y., assignor to
 William B. Robinson Corporation, a corpora-
 tion of Delaware

Application July 18, 1935, Serial No. 31,959

8 Claims. (Cl. 108—8)

This invention relates to a roofing strip that can be easily applied. The strip is made up of three principal parts all firmly attached or adhered together, one of the parts serving as a roofing deck, thus eliminating the necessity of first applying a deck to the rafters, another part serving as a heat insulating layer, and a third part serving as the shingle or water-proof portion of the strip. The strip can be fabricated at 5 the factory and shipped in convenient lengths ready for installation and use.

The invention will be understood from the description in connection with the accompanying drawing in which Fig. 1 is a plan view, partly 10 broken away, indicating a few of the strips laid one above the other on rafters; Fig. 2 is a transverse section along the line 2—2 of Fig. 1 and Fig. 3 is a transverse section across one of the strips on an enlarged scale.

20 In the drawing reference character 1 indicates a roofing strip which is of a length to span the space between two of the rafters 2 or the spaces between three or more of these rafters. The strips may be installed in such a way that the 25 joints between ends of adjacent strips come in a line or lines down the roof when the strips are not as long as the roof which they cover.

The base or bottom portion 3 of each strip is made of wood, or other rigid material. When 30 the roofing strips are installed the bases or bottoms 3 lie across the rafters with their edges in contact, as indicated in Fig. 2, so that they form a smooth roof deck.

A strip 4 of heat insulating material is applied 35 to the base 3 and is made to adhere thereto by any convenient cementing material, such as sodium silicate, tar, asphalt, etc. The strip 4 may very advantageously be made to contain or be substantially entirely composed of fibrous material such as sugarcane bagasse, wood fiber, asbestos, etc. The strip 4 is wider than the base 3 to provide a portion 5 which extends beyond the lower edge of the base 3, the top and bottom sides of this extending portion 5 being prefer- 40 ably parallel to each other. The remainder of the strip 4 is preferably made of wedge shape in cross section with the upper edge tapering to a thin portion, as shown at 6.

A strip 7 of water-proof roofing felt, such as a base of felt saturated with asphalt, tar or other bituminous material or the like to render it water-proof, is applied to the top side of the strip 4 of heat insulating material by means of any convenient adhesive or cementitious material. A layer 8 of wear-resisting mineral surfacing,

such as crushed stone, slate, etc., is applied to a large portion of the upper surface of the strip 7, leaving a portion 9 along the upper edge free from mineral surfacing. The portion 9 that is free from mineral surfacing may have a coating 5 of tar or other water-proof adhesive material applied to it to cause the next strip above to adhere thereto. Or copper sheet or other water-proof material may be used as the strip 7.

A water-proof strip 10 is applied along the 10 lower edge of the strip 4 and the lower side of the extending portion 5, as most clearly shown in Fig. 3.

When the strips 1 are installed so that there are joints at the ends, as shown in Fig. 1, a strip 15 11 of mineral surfaced roofing felt may be applied over the joints above the rafters where the ends of the strips 1 meet. The strip 11 may be applied by first applying tar, asphalt or other water-proofing adhesive material to the area 20 over which the strip 11 is to be applied, or the mineral surfacing 8 may be omitted for short distances along the ends of the respective strips 1 to facilitate application of the joint breaking strip 11, or overlapping shingles may be laid 25 over the joints as the strips are installed.

The strips made in accordance with this invention not only provide a roofing deck and heat insulation, as well as the wear-resisting water-proof layer, but the strip is also self spacing due 30 to the extending portion 5, as will be readily apparent from Fig. 2. Also, by applying a hot iron the asphalt or the like underlying the mineral surfacing 8 can be made visible so that lines simulating the appearance of shingles can be made 35 along the roof.

The bottom strip that is to be made along the edge or eave of the roof may be made with the entire portion of the heat insulating strip 4 made wedge shaped and with the base 3 of the same 40 width as the heat insulating strip, or the bottom strip may be filled in under the portion 5 with a wood strip or other material similar to that used for the portion 3, and the hips, valleys, etc., of the roof may be made safe from leakage by applying strips of water-proofing material there- 45 to, or in any other convenient way.

The portions 4 and 5 of the strip are advantageously made of material that is not only heat insulating but is also serviceable as sound-proofing material or sound-deadening material. The strips are suitable not only for use as roofing material, but also for siding as well. Instead of having the joints coming in lines down the roof the joints may be broken and individual shingles

as long as the width of the strips 7 may be installed at the same time that the strips are installed, with the upper ends of each of the shingles extending under the portion 5 of the strips 5 at the respective joints.

I claim:

1. A roofing strip comprising insulating material tapering in cross section, a base of uniformly thick stiffened material extending from the thinner edge of said insulating material to a point short of the other edge thereof and a layer of water proof material extending over the face of said insulating material.
- 10 2. A roofing strip comprising insulating material tapering in cross section, a base of uniformly thick stiffened material extending from the thinner edge of said insulating material to a point short of the other edge thereof, a layer of water proof material extending over the face 15 of said insulating material and a layer of water proof adhesive material extending from the terminus of said base portion to the thicker edge 20 of said strip.
- 25 3. A roofing and siding strip comprising a base having parallel sides, an intermediate portion of stiff heat insulating material having converging sides and having an extension projecting beyond said base when the two are in assembled relation, a water proof sheet on said intermediate 30 portion, and a water proof sheet extending along the end and under side of said extension.
- 35 4. A roofing and siding strip comprising a stiff base having parallel sides, an intermediate portion of stiff heat insulating material having converging sides, a water proof sheet on said inter-

mediate portion, and mineral surfacing on the upper surface of said waterproof sheet.

5. A roofing and siding strip comprising a base having parallel sides, an intermediate portion of stiff heat insulating material having converging sides and having an extension with parallel sides projecting beyond said base when the two are in assembled relation, and a water proof sheet on said intermediate portion.

10 6. A roofing and siding strip comprising a base of rigid material having parallel sides, an intermediate portion of stiff heat insulating material having converging sides and having an extension with parallel sides projecting beyond said base when the two are in assembled relation, and a 15 water proof sheet on said intermediate portion.

20 7. A roofing strip comprising insulating material tapering in cross section, a base of uniformly thick stiffened material extending from the thinner edge of said insulating material to a point short of the other edge thereof and a layer of preformed water proof material extending over the face of said insulating material.

25 8. A roofing strip comprising a base of uniformly thick stiffened material, insulating material tapering in cross section extending over said base from one edge thereof to the other, an extension of insulating material along the thicker edge of said insulating material having substantially parallel sides and extending beyond the 30 edge of said base, and a layer of water proof material extending over the face of said insulating material and said extension.

WILLIAM B. ROBINSON. 35
